CLAIM

The ornamental design for a cordless lamp, as shown and described.

DESCRIPTION

FIG. 1 is a top view of the cordless lamp;

FIG. 2 is a front view thereof with the rear view and side views being the same;

FIG. 3 is a bottom view thereof;

FIG. 4 is an isometric view thereof from above; and,

FIG. 5 is an isometric view thereof from below.

The broken line disclosure represents a portion of the cordless lamp which forms no part of the claimed design.
